UNITED STATES PATENT OFFICE.

CHARLES B. MANVILLE, OF YONKERS, NEW YORK, ASSIGNOR TO OTIS ELEVATOR COMPANY, OF JERSEY CITY, NEW JERSEY, A CORPORATION OF NEW JERSEY.

ELECTRIC ELEVATOR.

1,089,937.

Specification of Letters Patent. Patented Mar. 10, 1914.

Application filed May 16, 1912. Serial No. 697,608.

To all whom it may concern:

Be it known that I, CHARLES B. MANVILLE, a citizen of the United States, residing at Yonkers, in the county of Westchester and State of New York, have invented a new and useful Improvement in Electric Elevators, of which the following is a specification.

My invention relates to electric elevators, 10 and has for one of its objects the provision of means for preventing an elevator car from being operated other than by the proper apparatus arranged for that purpose.

Another object of my invention is the 15 provision of novel and efficient means for preventing the operation of the elevator should one of the doors be open.

A further object of my invention is to 20 prevent injurious arcing at the door or gate contacts of an elevator system.

Other objects will appear hereinafter, the 25 novel combinations of elements being pointed out in the appended claims.

The sheet of drawing accompanying this 30 specification illustrates diagrammatically an electric elevator system containing an embodiment of my invention, in which—

C designates an elevator car suspended from a cable F which is in frictional driving engagement with a sheave G driven by an electric motor D and which is connected at one end to a counterbalance weight W. This type of elevator apparatus is commonly known as a rope drive or traction 35 elevator, and while I have shown this type of elevator on account of its simplicity, it is to be understood that my invention is equally well adapted to any other type of elevator in which electricity is used in a 40 controlling circuit. A controlling switch apparatus is designated by E and is arranged to be operated from the car C by means of a hand rope H. The usual spring 45 pressed electrically released brake apparatus 45 is designated by B, while 10 represents the brake magnet which is used to effect the release of the brake. A main line magnet switch M operates to open or close a circuit 50 from the main line designated by + and - 55 to the motor and brake-releasing magnet. A safety switch is shown at S, while A 60 designates an accelerating magnet. The 65 trolleyway doors at each landing are designated by 1, 2, 3 and 4, while 5, 6, 7 and 8, 70 represent the contacts controlled by said doors, these contacts being closed when the corresponding doors are closed and vice versa, the uppermost door 4 being shown in open position. Gate contacts 9 are shown 75 in the car, and the same are open or closed by the car gate after the usual manner. An emergency switch 11 is located in the car, by means of which the operator can immediately stop the elevator at any time he sees fit. Top and bottom limit switches are 80 designated by 12 and 13, respectively, and the same are operated by the car in case the latter overruns its normal limits of travel in either direction. The controlling switch E, which is merely typical in character, comprises a sheave 14 secured to a shaft 15 and adapted to be rotated in one direction or the other by the hand rope H. The shaft 15 has affixed thereto a number of different shaped cams such as 16, 17, 18 and 19, adapted to 85 control corresponding switches such as 25, 24, 22 and 20, respectively. The accelerating magnet A comprises a number of contacts such as 26, 27 and 28, arranged automatically and gradually to short circuit a 90 starting resistance 29 so as to bring the motor D up to speed. The safety switch S comprises a solenoid winding 30 adapted when energized to raise a core 31 and mechanically connect contacts 32 and 34 out 95 of electrical engagement with corresponding fixed contacts 33 and 35, respectively. The main line magnet switch M comprises a solenoid 36 which is adapted when energized to raise a core 37, thereby closing a 100 number of contacts 39, 40, 41, and 42. A slack cable switch is indicated at 44 while a governor switch 45 is intended to open its contact upon excessive speed of the car, the 105 governor being connected in the usual manner to a tare at a speed proportional to that of the elevator car.

The operation of the apparatus just described is as follows: Assuming all of the landing doors are in closed position, the operator in the car pulls up on the hand rope H, thereby rotating the sheave 14, shaft 15 and cams 16, 17, 18 and 19 in a clockwise or right hand direction. Owing to the shape of these cams it will be observed that the 105 switch 25 and switches 22 and 20 will simultaneously move into closed position followed shortly afterward by the switches 24. The

switches 20 and 22 make the proper armature connection so that as soon as the motor circuit is closed, the motor will rotate in a direction to lower the car, while the switches 5 24 close a circuit to the magnet of the main line switch and to the brake magnet. These latter circuits may be traced from the positive main + by way of the conductor 46 to both of the contacts common to the 10 switches 24. The circuit branches at this point, part of it continuing by wire 47 through the governor switch 45, slack cable switch 44, through the winding 36 of the main line magnet M, through the contacts 15 34 and 35 of the safety switch S, and by the wire 48, this circuit continues through the switch 11 in the car, the limit switches 12 and 13, and by the wire 49 to the negative or — main. The main line switch now operates to close its contacts. The other branch 20 of this circuit passes through the contacts of the right hand switch 24, wire 50, contacts 42, through the brake magnet 10, and by way of the contacts 40 and 41 to the 25 negative or — main. The brake is now released and the motor circuit closed, this latter circuit being traced from the positive main +, through the contacts 39, wire 51, contacts of the right hand switch 25, contacts 30 23 of switch 22, armature brush 52, through the motor armature to brush 53, wire 54, contacts 21 of switch 20, wire 55, through the starting resistance 29, and by way of the wire 56 and contacts 41 to the 35 negative or — main. The motor now starts at slow speed to lower the car, the shunt field being connected by the contacts 39 and 41 across the line. The switch 25 connects the accelerating magnet A across the motor 40 armature and a small portion of the starting resistance so that it will operate gradually to short circuit the starting resistance and permit the motor to reach full normal speed. It will be observed that the safety 45 magnet does not operate at this time since its magnet winding 30 is short circuited by the door contacts 8, 7, 6, 5 and the car gate contact 9. The upper terminal of this magnet is connected through the wire 57 and 50 gate contact 9, through the door contacts 8, 7, 6 and 5, and by the wire 58 and contacts 32 and 33 and wire 59 to the lower terminal of the magnet, hence substantially no current will pass through the magnet and the 55 same will not operate its contacts. Should, however, one of the doors or the car gate be opened while the car is in motion, this shunt circuit around the magnet 30 is interrupted and the magnet immediately begins 60 energized to raise its core and connected contacts 32 and 34. The circuit of this magnet being traced from the positive main + by the wire 46, through the switch 24, wire 47, governor switch 45, slack cable switch 44, resistance 43, magnet winding 30, 65 wire 59, wire 48, switch 11 in the car, limit switches 12 and 13, and by wire 49 to the negative or — main.

The operation of the safety switch S interrupts the circuit to the magnet of the 70 main line switch M at the contacts 34 and 35 and the switch M drops its core, thereby opening the circuit to the motor and brake releasing magnet and the elevator immediately comes to rest with the brake applied. 75 If the car gate or one of the landing doors be open and an attempt is made to operate the elevator, it is readily seen that the safety switch is at once energized to open the circuit to the operating magnet of the main 80 line switch so that the latter cannot possibly get current to close the motor and brake circuits under this condition. Furthermore, there can be no destructive arcing at the 85 gate and door contacts at any time, since the circuit including these contacts is a mere shunt circuit around the magnet winding of the safety switch and when this shunt circuit is opened by opening a door, the small current passing therethrough is 90 merely diverted through the magnet of the safety switch and this current is of small amount being limited by the comparatively high resistance 43. The operation of the system in a reverse direction is effected in 95 the usual manner by giving an upward pull on the hand rope H. The cam controlled switches operating as before, with the exception of the switches 20 and 22, their companion switches operating instead so as to 100 reverse the motor armature connections and cause the motor to rotate in the opposite direction.

In the ordinary practice, if a door or gate be opened while the car is in motion the 105 operating circuit is interrupted and the elevator brought to rest. As soon, however, as the door is closed the car will immediately start again in the same direction of travel as before. With this arrangement 110 the car operator soon learns that he can start and stop the car by merely opening or closing the car gate, or where the speed of the elevator is moderate and the car is not provided with a gate, he can reach out 115 while the car is in motion and open a landing door which will stop the car. While this method of controlling the starting and stopping of an elevator may involve less labor than is required to manipulate the 120 controller, particularly when the controller is operated by means of the well known hand rope, it is at best a very dangerous practice, and an elevator system which permits of this false operation should not be 125 countenanced, particularly in view of the numerous and sometimes fatal accidents from this cause alone, which are of almost

daily occurrence. My invention entirely overcomes this and other objectionable features, since the operator in the car must of necessity first bring the controlling switch to its center or "off" position every time the car is stopped, before he can again start the car, and in starting the car it is absolutely necessary to manipulate the proper controlling means, whether the same be a hand rope or car switch or lever or other device. This feature of my invention is of great practical importance as regards the comfort and safety of the occupants of the elevator, and I attain the desired end by means comprising the safety magnet switch S. In connection with this switch, it will be observed that should any one of the landing doors or the car gate be opened and the car stopped in its travel, the subsequent closing of such door or gate will not operate to start the elevator. This is because the operation of the safety switch open circuits the door and gate contacts at the switch contact 32, hence the closing of the door or gate contacts can have no effect whatsoever on the system, as the safety switch will remain energized or in its operated position just so long as its circuit remains closed at the controlling switch E, the latter establishing a self holding circuit for the safety switch S over which the door and gate contacts have no control. The controlling switch E must be centered in order to interrupt this self holding circuit for the safety switch, and the controlling switch again be moved to operating position by the appropriate means before the car can again be operated. By means of my invention, the operator must manipulate the controlling mechanism every time he desires to start the car and for this reason the safety and comfort of the passengers is not placed in jeopardy by any act of an incompetent or careless operator.

Sometimes the main operating circuit is carried through the door contacts so that in case a door be opened while the car is in motion, the operating circuit will be broken and the motor stopped. In such case the entire current of the operating circuit is broken at one of the door contacts and the arc produced will be considerable and will rapidly destroy the door contacts, more particularly since these contacts must of necessity be of small dimensions and rather delicate and furthermore are usually placed in an inaccessible place out of sight. My invention overcomes the damaging effects of arcing at the contacts in a novel and practical manner, since at no time can there be any appreciable sparking at the door contacts.

For purposes of illustration I have shown and described a hand rope operated electric

elevator, but it is to be understood that my invention is adapted to any and all electric elevators in which door or gate contacts are used to prevent operation of the elevator when a door or gate is opened.

What I claim is new and desire to secure by Letters Patent of the United States is:

1. In an electric elevator, the combination of a hoisting motor, an electro-responsive device for opening and closing the motor circuit, a normally closed safety switch in the circuit of the operating solenoid of said electro-responsive device, a solenoid for effecting the operation of said safety switch, door contacts arranged at the floor landings, a circuit including said door contacts arranged in shunt to said solenoid, and a resistance in series with said solenoid and door contacts.

2. In an electric elevator, the combination of a hoisting motor, a main line switch for opening and closing a circuit to said motor, electro-magnetic means for effecting the operation of said main line switch, door contacts arranged at the floor landings, a normally closed magnet controlled safety switch in the operating circuit of said main line switch, and a circuit including the door contacts arranged in shunt to the controlling magnet of said safety switch for short circuiting the same when the landing doors are in closed position.

3. In an electric elevator, the combination of an electrically controlled switch, a safety magnet switch in circuit with the operating magnet of said switch, a normally closed shunt around the magnet of said safety switch, and means associated with a landing door for opening said shunt upon opening said landing door.

4. In an electric elevator, the combination of a main line switch, means operated from the car for effecting the operation of said switch, an electrically operated safety switch controlled by a hatch door for rendering said switch inoperative, and a self holding circuit for said safety switch established by the operation of said hatch door, said circuit being controlled by said first named means.

5. In an electric elevator, the combination of a car, a main line switch, means controlled from the car for effecting the operation of said main line switch, means independent of said main line switch set into operation by the opening of an elevator door for rendering said main line switch inoperative unless and until said controlling means be first moved to "off" position.

6. In an electric elevator, the combination of means comprising a main line switch controlled from the car for starting and stopping the latter, means independent of said main line switch operated by the open-

ing of a door for rendering said starting and stopping means inoperative and for preventing the car from again being operated unless and until the door be closed and the starting and stopping mechanism be moved to "off" position.

In testimony whereof, I have signed my

name to this specification in the presence of two subscribing witnesses.
